UNITED STATES PATENT OFFICE.

BURNS D. LOCKWOOD, OF BELLEVUE, AND JOHN F. STREIB, OF AVALON, PENNSYLVANIA, ASSIGNORS TO PRESSED STEEL CAR COMPANY, OF PITTSBURGH, PENNSYLVANIA, A CORPORATION OF NEW JERSEY.

CAR-TRUCK.

1,358,320.

Specification of Letters Patent.

Patented Nov. 9, 1920.

Application filed August 3, 1920. Serial No. 400,904.

To all whom it may concern:

Be it known that we, BURNS D. Lockwood and JOHN F. STREIB, citizens of the United States, residing in Bellevue and Avalon, respectively, in the county of Allegheny and State of Pennsylvania, have invented certain new and useful Improvements in Car-Trucks, of which the following is a specification.

10 An object of the present invention is to provide a six wheel truck, the frame of which will be rigid, light, simple and cheap in construction and efficient.

Another object of the invention is to construct a truck having a very rigid frame and in which the wheels, axles and journal boxes are mounted in such a manner as to readily compensate for unevenness of tracks and curves therein without affecting the

20 rigidity of the truck frame.

A further object of the invention is to provide novel side or wheel pieces and novel connections between such pieces and the transoms or transverse members of the frame.

25 These and other objects will be apparent from the following description:

Referring now to the drawings in which like reference characters refer to like parts, Figure 1 is a plan view of the truck constructed in accordance with the invention; Fig. 2 is a composite view of the same the left hand half being a sectional view taken on the line 2—2 of Fig. 1, and the right hand half being a side elevational view of 35 a portion of the truck; Fig. 3, is a composite view, the left hand half being a sectional view taken on the line 3—3 of Fig. 1, and the right hand being an end elevational view of a portion of the truck, 40 and Fig. 4, is a sectional view taken on the line 4—4 of Fig. 1.

Referring now in detail to the drawings, the reference character 1 indicates the truck frame which comprises side pieces 2, end pieces 3, transverse members 4 intermediate the end pieces and a center bearing or bridge member 5. The side pieces 2 are arranged at the sides of the truck frame and each one of them comprises a horizontally disposed web 6 having an inner downwardly depending portion 7 and an outer downwardly depending portion 8. These pieces 2 extend for substantially the full length of the truck and at their ends are provided

with pedestals 9 each of which is provided 55 with an outer flange 10 which is secured to the outer portion 8 of one of the side pieces 2 and is further provided with an inner flange 11 which is secured to the inner portion 7 of the side piece. Each of the side pieces intermediate its ends is provided with a pedestal 12 having flanges 10 and 11 which are secured to the portions 8 and 7 respectively of the side piece 2. Each one of the pedestals is provided with a jaw in which a 60 journal box 13 is movably mounted. The axles 14 of the truck are rotatably mounted in the journal boxes and are provided with 65 wheels 15. Between the pedestals 9 and 12, the outer portion 8 of each of the pieces 70 2 is provided with outwardly extending flanges 16 which are adapted to strengthen the piece 2 as a whole.

The members 4 extend transversely for substantially the full width of the truck 75 frame and are so arranged that there will be one of such members at each side of the transverse center line of the truck and in a plane below the side pieces 2. Each of these members is preferably of I form in cross section having its web 17 disposed of vertically and its top and bottom flanges 18 and 19 respectively disposed horizontally on each side of the web 17. At their ends the top flanges 18 are cut away and the vertically 85 disposed web 17 and the bottom flanges 19 of the member pass under the side pieces 2, the bottom flanges resting on and being secured to the horizontally disposed web 20 of a channel shaped member 21, the 90 ends of such member 21 being secured to lugs 22 on adjacent pedestals. The end portions of each of these transverse members 4 are connected with the side pieces 2 through the medium of channel shaped members 23. The webs of these members extend in a direction transversely of the truck and their flanges 24 and 25 extend in a direction longitudinally of the truck. At each end of each member 4, two of these 100 members 23 are provided the backs of the webs of which, at their lower ends, contact with and are secured to the web 17 of the member 4. The upper end portion of each of the flanges 24 is secured to the inner depending portion 7 of one of the side pieces, and the upper portion of each of the flanges 25 is secured to the outer depending portion 105

8 of such side piece, there being a plate 26 interposed between the flanges 25 of two adjacent members and the outer depending portion 8 of the side piece, such plate extending below the side piece and having its lower portion secured to the flanges 25 and to a flange of one of the channel shaped members 21. To further connect the members 4 with the side pieces 2 flanged plates 10 27 are provided each of which has a vertical flange 28 which is secured to the portion 7 of one of the side pieces 2 and has a horizontal flange 29 which is secured to the top flanges of one of the transverse members 4, 15 there being a plate 30 interposed between the flange 29 and the flanges of the member 4 such plate being of substantially the same length as the two flanges of the member 4. These plates serve to strengthen the 20 members 4 and also form seats for the ends of the bridge member 5.

The bridge or center bearing member 5, is preferably of H form having two parallel members 31. The members 31 extend in a 25 direction longitudinally of the truck and at their ends rest on and are secured to the plates 30 and the top flanges of the members 4. The transverse member 32 is provided with a center plate 33 which is some 30 distance below the top portions of the members 31. The under side portion of this member 32 is so formed that it will arch over the center axle of the truck to permit a sufficient relative movement between the 35 bolster and the axle.

Between the side pieces 2 and the journal boxes 13, springs 34 are provided the lower ends of such springs being seated on the journal boxes and the upper ends being 40 seated on members 35 which are secured to the web 6 of the side pieces 2, thus substantially inclosing the springs within the side pieces 2.

Having thus described the invention what 45 we claim as new and desire to secure by Letters Patent is:—

1. A car truck comprising side pieces having inner and outer downwardly depending portions, pedestals secured to said

portions, members connecting said pedestals, and members extending transversely of said truck the end portions of said members resting on and being secured to the first mentioned members and channel shaped members for connecting said transverse 55 members and said side pieces.

2. In a car truck, side pieces, pedestals mounted on said pieces, longitudinally disposed members secured to said pedestals, transverse members between said pedestals 60 secured to said longitudinally disposed members, and vertically disposed channel members secured to said pieces and members.

3. In a car truck, side pieces having inner and outer depending portions, outwardly 65 extending horizontally disposed flanges on said pieces, a pedestal secured to said depending portions, longitudinally disposed members secured to said pedestals, transverse members arranged in a plane below 70 said pieces and adapted to rest on said longitudinal members, a vertically disposed channel shaped member secured to said pieces and transverse members.

4. In a truck, side pieces, transverse members connected with said pieces, pedestals secured to said pieces, longitudinal members disposed below said side pieces and secured to said pedestal, said members comprising a seat for said transverse members, 75 and a center bearing member of H form secured to said transverse members.

5. In a truck, side pieces, transverse members disposed below said pieces, said members having upper and lower flanges, said 80 upper flanges being cut away below said pieces, vertically disposed members secured to said transverse members below where said upper flanges have been cut away and to 85 said pieces.

In testimony whereof we affix our signatures in the presence of two witnesses.

BURNS D. LOCKWOOD
JOHN F. STREIB.
